[57] CLAIM

The ornamental design for physical exercise apparatus, as shown and described.

DESCRIPTION

FIG. 1 is a top plan view of a physical exercise apparatus showing my new design;

FIG. 2 is a right side elevational view thereof, the left side view being a mirror image thereof;

FIG. 3 is a perspective view of the physical exercise apparatus of FIG. 1;

FIG. 4 is a perspective view thereof, the broken line showing of the person being for illustrative purposes only and forming no part of the claimed design;

FIG. 5 is a front elevational view of the physical exercise apparatus of FIG. 1; and,

FIG. 6 is a rear elevational view of the physical exercise apparatus of FIG. 1.
